UNITED STATES PATENT OFFICE.

ALGOTH N. ANDERSON, OF LEAL, NORTH DAKOTA.

LOADER.

1,381,053.

Specification of Letters Patent. Patented June 7, 1921.

Application filed May 18, 1916. Serial No. 98,358.

To all whom it may concern:

Be it known that I, ALGOTH N. ANDERSON, a citizen of the United States, residing at Leal, in the county of Barnes and State

5 of North Dakota, have invented certain new and useful Improvements in Loaders; and I do hereby declare the following to be a full, clear, and exact description of the invention, such as will enable others skilled

10 in the art to which it appertains to make and use the same.

This invention relates to a device which is particularly designed for facilitating the loading of manure, dirt or analogous material in a wagon bed, and the primary object of the invention is to provide a loader upon which manure, dirt or the like may be dumped from a scraper of ordinary construction, and carried upwardly and deposited in a wagon, thereby eliminating the slow and laborious work of loading the wagon by a shovel or fork.

Another object of this invention is to provide a loader as specified, which includes 25 a horizontally positioned conveyer, and an inclined elevator which receives manure, dirt or the like from the delivery end of the horizontally positioned conveyer and delivers it to a wagon bed or suitable structure.

30 A further object of this invention is to provide approaches which lead to the horizontally positioned conveyer so that the person using the loader may drive the team and scraper up on to one of the approaches, 35 for dumping the contents of the scraper upon the horizontally positioned conveyer, and drive on across the conveyer and down off the other approach and also to provide a bar which extends across the upper ends 40 of the approaches and is provided for being engaged by the forward end of the scraper for facilitating the dumping of the same.

A further object of this invention is to 45 provide a novel gear structure for regulating the speed of travel of the elevator.

With the foregoing and other objects in view this invention consists in such novel

features of construction, combination and arrangement of parts as will be hereinafter 50 more fully described, illustrated in the accompanying drawings and claimed.

In describing the invention in detail reference will be had to the accompanying drawings wherein like characters designate 55 like and corresponding parts throughout the several views, and in which:—

Figure 1 is a top plan view of the improved loader,

Fig. 2 is a longitudinal section of the 60 loader,

Fig. 3 is a cross section through the loader on the line 3—3 of Fig. 1,

Fig. 4 is a detail view of end of the supporting structure of the horizontally positioned conveyer, and

Fig. 5 is a detail view illustrating the gear structure.

Referring more particularly to the drawings, 1 and 2 designate the supporting beams 70 of the horizontally positioned conveyer structure, which beams have side boards 3 and 4 attached to their upper edges, between which the conveyer 5 travels. The conveyer 5 comprises sprocket chains 6 75 which have a plurality of flights 7 attached thereto in close proximity to each other, as clearly shown in Fig. 1 of the drawings, so as to prevent manure from falling between the flights or slats of the conveyer. 80 The supporting frame work, of which the boards 3 and 4 form the sides has a plurality of spaced studs 8 carried thereby, to which are attached a plurality of rollers 9. The rollers 9 are positioned so that they 85 will engage the under surfaces of the flights 7 of which the conveyer is formed and they are positioned very close to each other, being rotatably mounted upon suitable pins 10 which are carried by the spaced studs. 90

The sprocket chains 6 travel about sprockets 11, which are carried by shafts 12 and 13. The shaft 12 is positioned at one end of the conveyer structure while the shaft 13 is positioned at the delivery end of the 95 conveyer. The shaft 12 is rotatably sup-

ported by bearing blocks 14, which bearing blocks are slidably mounted in recesses 15 formed in the side boards 3 and 4. Screw-threaded pins 16 are connected to the bearing blocks 14 and nuts 17 are mounted upon the pins 16 so that upon rotation of the nuts, the bearing blocks will be moved inwardly or outwardly for regulating the tension of the conveyer.

10 An elevator structure generically indicated by the numeral 20 is supported by suitable supports 21 which are connected to the beams 1 and 2 and it includes side braces 22, which have a plurality of rollers 23 rotatably supported thereby. The rollers 23 are identical in construction to the rollers 9, and they support the upper run of the endless conveyer or belt structure 24 of the elevator. The endless belt structure 24 includes sprocket chains 25 which have flights or slats 26 attached thereto. The chains 25 travel about sprockets 27 and 28 which are mounted upon shafts 29 and 30 respectively. The shaft 30 is carried by the upper end of the side boards 22 of the supporting structure of the elevator and it has a sprocket 31 mounted thereon about which a drive sprocket chain 32 travels. The drive sprocket chain 32 also travels about a 30 sprocket 33 which is carried by a shaft 34. The shaft 34 has gears 35 and 36 mounted thereon which are adapted for making engagement with gears 37 and 38 which are carried by a shaft 39. Any suitable gear shifting mechanism may be employed for shifting the gears 34 and 35 into meshing engagement with the gears 37 and 38. The shaft 39 has a pulley 40 mounted thereon, through the medium of which power is 40 transmitted from any suitable type of prime mover to the shaft. The pulley 40 is an ordinary type of clutch pulley, and the clutch mechanism is operated by the pivotal movement of a lever 41, which is pivotally mounted as shown at 42. The gear 43 is mounted upon the shaft 13 and it meshes with the gear 37 for operating the transversely or horizontally positioned conveyer by the operation of the shaft 39. A gear 50 casing 44 is provided for covering and protecting the gear.

Idlers indicated at 45 are provided, which support the lower run of the conveyer 24.

Approaches 46 and 47 are provided for 55 facilitating the driving upon the upper run of the horizontal conveyer structure 5 and they have depending boards 48 attached to the under surface of their upper ends said boards resting upon the upper edges of the 60 beams 1 and 2. Cleats or bars 49 are attached to and extend transversely across the upper surface of the upper ends of the approaches 46 and 47 and they facilitate the dumping of a scraper upon the conveyer 5,

in that the front or forward edges of the 65 scraper engages the outer edge of the bars or cleats so that the forward movement of the horses will tend to dump the scraper upon the conveyer.

In operation of the improved loader: the 70 manure or dirt is hauled to the loader in ordinary dump scrapers, and the scrapers are drawn upwardly over one of the approaches until the forward edge of the 75 scraper engages one of the cleats 49, which will permit the scraper to dump its load upon the upper run of the horizontally positioned conveyer 5. The movement of the conveyer 5 will deliver the manure or dirt to the elevator structure 20 which will elevate the same and deposit it into a wagon bed or the like while the scraper is drawn over the conveyer and down the opposite approach.

In reducing the invention to practice certain minor features of construction, combination and arrangement of parts may necessitate alterations to which the patentee is entitled provided such alterations are comprehended within the scope of what is claimed.

What is claimed is:—

1. In a loader, a constantly moving member serving as a conveyer and as a tread means for a draft animal hauling material to the member, and approach means associated with the member permitting travel of the animal directly on and across the member while the latter is in motion.

2. In a loader, a constantly moving member serving as a conveyer and as a tread means for a draft animal hauling material to the member, approach means associated with the member, permitting travel of the animal directly on and across the member while the latter is in motion, and abutment means associated with the approach means to coöperate with the material carrier to dump the material onto the member as the animal travels across the same.

3. In a loader, a constantly moving member serving as a conveyer and as a tread means for a draft animal hauling material to the member, a conveyer to receive material from the said member, and means operable to move the second conveyer independently of the first conveyer so as to increase its speed without increasing the speed of the first conveyer and consequently frightening the animal passing thereover.

4. In a loader, a movable member serving as a conveyer and as a tread means for a draft animal hauling material to the member, approaches associated with the conveyer on opposite sides thereof in substantial alignment, mounting means for the member, said approaches being supported by the mounting means, an abutment on one of the ap-

proaches to coöperate with the material carrier to dump the material onto the member as the animal travels across the same, a conveyer to receive the material from the first 5 conveyer, means to drive said conveyers simultaneously, and the last mentioned means being operable to move the second conveyer independently of the first conveyer so as to increase its speed without increasing the

speed of the first conveyer and consequently frightening the animal passing thereover.

In testimony whereof I affix my signature in presence of two witnesses.
